(57) **CLAIM**

The round multi-faceted diamond, shown and described in the drawings.

DESCRIPTION

FIG. 1 is a top plan view of the round multi-faceted diamond design;

FIG. 2 is a bottom plan view of the round multi-faceted diamond design; and,

FIG. 3 is a front plan view of the round multi-faceted diamond design of this invention.

No right side or left side views are presented as these would be identical to FIG. 3.
